HOSIERY REKNITTING NEEDLE

Beatrice Georgi, Yonkers, N. Y.

Application June 17, 1944, Serial No. 540,805

6 Claims. (CL. 66—117)

1

The present invention relates to hosiery reknitting needles, and is more particularly directed toward reknitting needles adapted for high speed operation from a power operator.

As is well known the mending or reknitting of hosiery includes the use of a hook which picks up the loop at the lower end of a ladder or run, and then passes this loop over the first course of the ladder, then picks up this ladder course, forms it into a loop and passes it over the next course of the ladder, this operation proceeding until the entire length of the run has been reknitted. During the operation each loop is successively passed beyond a latch and then is discharged from the needle over the latch so as to be released on to the next loop.

Hand operated devices for these purposes are well known, but they have been unsatisfactory for use in high speed power operated reknitting devices because of the likelihood of the hook picking up more than one thread at one time or of the latch overlapping more than one thread, either of which would result in an imperfect knit.

The present invention contemplates providing a reknitting needle having a very small hook and very small latch which substantially reduce the possibility of picking up or overlapping more than one thread and employing a guard which spaces the threads or courses and makes it possible to pick up one thread only at a time. As the needle is reciprocated back and forth this guard enters between two courses of the ladder next beyond the course which has already been received in the hook to form a loop, and guides one of these courses toward the hook and latch and forces the other course forwardly so that it does not get to the hook and latch.

Other and further objects will hereinafter appear as the description proceeds.

The accompanying drawings show, for purposes of illustrating the present invention, an embodiment in which the invention may take form, it being understood that the drawings are illustrative of the invention rather than limiting the same.

In these drawings:

Figure 1 is a fragmentary perspective view illustrating a power operated reknitter in use;

Figure 2 is an enlarged perspective view of the power operator and needle;

Figure 3 is a side elevational view of the needle at a greatly enlarged scale;

Figure 4 is a view taken in the direction of the arrow 4 of Figure 3;

Figure 5 is a perspective view illustrating the

2

first step in starting a reknitting or mending operation;

Figure 6 is a side elevational view of the reknitting needle taken in the plane 6—6 of Figure 5 looking in the direction of the arrows, this figure showing in heavy full lines the needle as it is about to be inserted into the fabric, in light full lines the position when it has been lowered into the fabric to cause the run to extend to a loop which is caught in the hook, and in light dotted lines the position when it has been lifted up and moved forwardly to carry the loop in front of the last rung of the ladder; and

Figure 7 is a view showing in heavy full lines the needle at the end of the next down stroke where the loop is above the latch and the ladder course caught in the hook, in light full lines the end of the out stroke before moving forwardly, and in dotted lines the forward movement.

Figure 1 illustrates the use of the hosiery repairing machine which includes a fixed stroke needle reciprocator 20 preferably a magnetic device powered from an electronic impulse sender. It is held in one hand at about the sloping position indicated in Figure 1, while the stocking is held over a mending cup 21 by the other hand.

The hand operated tool includes in addition to the needle reciprocator a needle generally designated by the reference character N. This needle is provided with a supporting bar or shank 22 by which it may be detachably secured to the needle reciprocator.

This bar or shank is preferably a thin piece of stiff steel and has a hook 23 which extends back parallel with the general direction of the needle and has a point indicated at 24. The shank also has a hump portion 25 slotted as indicated at 26 to receive a latch 27. The latch is pivoted as indicated at 27' and is movable from a position where it overlies the point of the hook as indicated in full lines in Figure 3 to an upper position above the hump.

The reknitting needle is also provided with a guard 28 having one portion 29 attached to the shank or bar some distance above the upper position of the latch 27. The lower portion of the guard, indicated at 30, is disposed laterally of the hump, the latch and the point of the needle so as to provide a narrow space 31 adapted to be traversed by the thread. The guard has a straight rear surface indicated at 32 which is preferably even with the top of the hump 25. It has a front surface 33 which slopes toward the point of the needle and acts to deflect one ladder course toward the hook, a rounded nose 34 and a front

50 surface 35 which slopes toward the point of the needle and acts to deflect one ladder course toward the hook, a rounded nose 34 and a front

edge 35 which is generally parallel with the shank and spaced forwardly at a suitable distance to enter behind the second ladder course.

Figure 5 illustrates a typical hosiery run. A number of unimpaired courses of hosiery are indicated at A, B, C, D, E and two ladder courses at F and G. The needle N is pressed against the loops below the ladder, as indicated in Figures 5 and 6. Here the needle is being pushed in between the threads forming courses A and B. The needle is slightly wider than the normal spacing of the courses of thread in the hosiery, and as the needle moves from the full line position in Figure 6 down into the fabric it spreads A and B slightly apart, causes the run to extend down to the needle so that the threads or courses D, C and E now become rungs of the ladder.

When the needle has been pushed down far enough to bring the loop B against the bottom side of the latch 27, it lifts this latch and passes under the latch and inside the point of the hook. This is indicated in light full lines in Figure 6 where the position of the thread B is indicated at B'. The needle is then moved upwardly so as to withdraw it from the fabric with the thread B in the bottom of the hook and the entire needle is moved forwardly as indicated in the dotted line position of Figure 6. Now thread B in the position indicated at B'' is above the fabric level. The needle is then moved downwardly to the position indicated in heavy full lines in Figure 7. This will cause the thread B to lift the latch 27 to the upper position and pass by it to arrive at the position indicated at B'''. At substantially the same time the ladder thread C is deflected toward the hook and passes inside as indicated at C', and when the needle is lifted to the position shown in light full lines in Figure 7, the loop B causes the latch to move to the lower position so that the loop B is discharged over the latch and over the thread C which is still in the hook, and the latter becomes a new "loop." When the needle is moved to the dotted line position of Figure 7 the thread C is in the position of C'' corresponding with the thread B'' at the end of the previous up stroke.

It will be noted from Figure 6 that the overall width of the needle is approximately the same as the spacing of three courses of the threads of the knitted fabric. The needle itself is slightly wider than the space between two adjacent threads so that these threads are slightly separated when the needle is in the fabric. The overall width including the guard and the needle is such that when the needle is pushed down into the fabric, as indicated in Figure 7, the lower surface of the guard has engaged the thread C and guided it next the point of the hook. At the same time the forward surface 35 of the guard has passed down behind thread D so that there is no possibility of thread D passing into the hook along with thread C. Furthermore it will be noted that the guard extends beyond the point of the latch 27 so that the latch moves back and forth in a region in which it is impossible for the latch to engage or overlap any thread except the one thread which is about to pass under it and get into the hook.

The construction shown and described herein is one which has been found to be extremely well adapted for use with high speed, fixed stroke magnetically controlled devices and operating at speeds of several thousand strokes a minute. In using the needle the operator manually picks up the first loop and can, if desired, operate the de-

vice manually to take a few stitches, but usually the power is applied and the reknitting accomplished over the distance permitted by the mending cup.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. The improvement in a hosiery reknitting needle having a shank, a pointed latch pivoted to the shank, the shank having a hump adjacent the pivot for the latch and a hook having its free end adjacent to but spaced from the hump to admit a thread, the latch protruding beyond the hump and being swingable between an inner or lower position where a loop already knitted into the hosiery fabric may be passed from inside the hook over the hump and up beyond the end of the latch and be received on the shank, and an outer or lower position opposite the end of the hook so that the said loop may be discharged over the hook, which improvement comprises a guard carried by the shank terminating adjacent the point of the hook and laterally spaced from the point of the hook, from the hump, and from the latch and the portion of the shank receiving the loop from the latch, the guard having a lower edge aligned with the point of the hook for deflecting a ladder run towards the latch and a front face spaced beyond the path of the point of the latch and adapted to enter behind the next rung.

2. A hosiery reknitting needle having a hook, a pointed latch and a shank generally disposed in one plane and a ladder-thread separating guard lateral of the shank, from the latch and from the point only of the hook for separating the ladder threads so that only one such thread enters the hook, its lower edge being aligned with the point of the hook.

3. A hosiery reknitting needle having a hook adapted to be passed through the space between two successive hosiery courses and pick up the loop at the end of a ladder and pass it forward of the lower rung of the ladder, a pointed latch beyond which the loop may pass from the hook when the hook picks up the said ladder rung to form a second loop and for discharging the first loop over the second loop, the latch and hook, and a guard alongside the latch and point only of the hook for facilitating the entry of the lower course of the ladder into the hook below the latch while the first loop is above the latch, and for nosing the next course of the ladder away from the point of the hook so that the hook receives only one ladder course at a time, the front edge of the guard being beyond the path of the point of the latch.

4. A hosiery reknitting needle having a hook adapted to be inserted into hosiery fabric so as to pick up a loop of such fabric, and a guard having a lower surface extending away from the hook and point at an acute angle with the hook point axis so as to guide a thread toward the hook, the guard being disposed laterally of the point only of the needle and extending forwardly to intercept the courses in advance of the loop being picked to keep it away from the hook.

5. A hosiery reknitting needle having a shank, a hook whose width is slightly greater than the normal spacing of the courses of thread in hosi-

ery so that when inserted into a loop it stretches the loop and the loop readily enters the hook, and a pointed latch pivoted to the shank and having its point movable toward and away from the point of the hook, and a guard lateral of the latch and point only of the hook, the width of the guard being sufficient to deflect one rung thread toward the latch and hold away from the point of the latch the adjacent ladder thread.

6. A hosiery reknitting needle having the usual hook and latch which when operated in the usual manner is adapted to convert a hosiery ladder into reknitted fabric, and provided with a guard along side the latch and point only of the hook and having a reentrant end surface for facilitating the entry of the lower course of the ladder into the hook below the latch while the first loop is above the latch, and a front edge beyond the path of the point of the latch for nosing the next course of the ladder away from the

5 point of the hook so that the hook receives only one ladder course at a time.
